UNITED STATES PATENT OFFICE

WILLIAM McCOY, OF ZANESVILLE, OHIO, ASSIGNOR TO AMERICAN ENCAUSTIC TILING COMPANY, LTD., OF NEW YORK, N. Y., A CORPORATION OF NEW YORK

TILE SETTER

Application filed July 3, 1928. Serial No. 290,231.

This invention is a means for exposing ceramic ware to the heat of a kiln in the heat treatment of the ware, and it is useful, more particularly, in the operations of glazing 5 wall and floor tile, although the principle of the invention is available for the heat treatment of ceramics generally and ceramic products generally.

One object of the invention is to provide 10 for the assembly of a substantial number of ceramic products after the latter shall have been coated with a glazing substance, and to retain the same in spaced order for exposure to high heat within a kiln or other 15 chamber, with a view to subjecting said coated products to heat treatment whereby the coatings are baked and developed into glazes upon the surfaces of the products.

My invention is embodied in a one piece 20 carrier in the form of a rack comprising a base, a plurality of columns extending upwardly from said base, and a top member in the form of a crown functioning as means for protecting the assembled coated products 25 from exposure to foreign materials which have a tendency to drop from the ceiling of the kiln chamber.

The base and the top member are in one 30 piece with the columns, resulting in a skele- tonized rack-like structure all the parts of 35 which are open for the unobstructed flow of heat and gases into the required contact with the coated surfaces of the products. It is usual to employ two columns, extending be- 40 tween the base and the top member, and said columns are perforated to produce openings for the flow of heat and gases. Means for supporting the ceramic products are provided upon the columns, said means being in the 45 form of narrow shelves positioned for the shelves of one column to lie in the planes of the similar shelves on the companion column, whereby an operator is enabled to load the carrier with tiles by the mere act of sliding 50 the tiles between the columns and upon the shelves, and in like manner, after the rack and its load shall have been removed and cooled, the tiles may be discharged by either removing the tiles individually or by dumping them by a sliding motion out of the rack.

The shelves on the rack columns alternate with the perforations in said columns, so that heat may flow below and above the tiles, and each shelf is bounded on one side by a direct- 55 ing ledge or shoulder parallel to the shelf and functioning as means for guiding the tile in the sliding movement when loaded or unloaded.

It is preferred to use the rack of my in- 60 vention in connection with a glazing kiln of the character disclosed in Prouty Patent No. 1,613,054, wherein the ware to be treated is loaded on conveyor-slabs composed of heat 65 resisting material. When so used, a rack is deposited upon each conveyor-slab the movement of which transports the loaded racks within the muffle chamber of a kiln for exposure of the coated tiles to the required 70 heat treatment. Under these conditions, it is desirable to anchor the loaded carriers or 75 racks to the corresponding conveyor-slabs, for which purposes I provide the base of each rack or carrier with an opening, and employ a draft pin or lug on the corresponding con- 80 veyor-slab, which pin or lug enters the opening and thus affords temporary anchor- 85 age for the rack upon the conveyor-slab, the effect of which is to insure the movement of the loaded rack with the conveyor slab and to preclude the dislodgment of the loaded 90 rack with respect to said conveyor-slab.

In the service of conveyor slabs within a muffle kiln it is found that there is a tendency, at certain periods, for débris from the kiln 95 walls or roof to lodge upon the coated surfaces of the tiles, or drops of glazing material accumulating upon the roof of the kiln chamber may become deposited upon the coated tiles, resulting in defective or imperfect products, degrading them. The employment of my racks overcomes this objection for the reason that the top member acts as a roof for the tiles loaded in the rack, said roof being imperforate in construction and the area of said roof extending the area of the individual tiles which are loaded in spaced order upon the shelves of the rack.

It is preferred to construct the base mem- 100 ber of the rack in a way for the heat and gases present in the muffle chamber to have access

freely to the undersurface of the base member, equalizing the effect of the heat and gases upon the material composing said base member, and thus minimizing a tendency of the base member to crack under the effect of the heat, resulting in prolonged service of the tile setter.

Other functions and advantages of my invention will appear from the following description taken in connection with the drawings, wherein—

Figure 1 is a vertical cross section through a muffle kiln illustrating my tile setters positioned for movement therein by conveyor slabs, two of said tile setters being shown in different positions within a plurality of muffle chambers.

Figure 2 is a perspective view of one of my tile setters detached from the kiln, showing said setter on a larger scale.

Figure 3 is an elevation of the setter imposed upon a conveyor slab, the latter being in section, and the draft pin being shown to afford anchoring means for the tile setter upon the conveyor slab.

Figure 4 is an inverted, or bottom, plan view of the tile setter, illustrating the formation of the bottom for the flow of heat and gases below the setter.

The device, called a setter for convenient designation, embodies in its construction a bottom member or base A, a top member or roof B, and a plurality of columns C, D, extending between the bottom and the top, all of the parts constituting a unitary structure for convenience in handling. According to my invention, the setter is a one-piece device, being cast in appropriate molds and composed of a substance or a composition which is suitable for molding and which is "fired" in an appropriate kiln for producing a vitrified product capable of withstanding the high heat employed in kilns for firing the coating applied to ceramic products whereby a glaze is produced on such products.

The base A is a part of generally flat rectangular form the under surface of which is channeled to provide for the free flow of heat below the setter. A convenient form of such channeling is shown in Figure 4, wherein the channels a , a' , extend lengthwise and crosswise of the surface. Said channels a intersect with channels a' , and the channels open through the edges of the base member, resulting in webs a^2 whereby the base is adapted to rest upon a conveyor-slab H in a way to slightly raise the body portion of the base and thus allow the heat and gases to have free access to the channels a , a' , the result of which is that all parts of the base are exposed to heat and said base becomes heated.

The columns C, D, are parallel with each other and at right angles to the base and the top. To reduce a tendency to fracture under the heating and cooling operations, each col-

umn is of channeled formation, reducing the cross section of heat-resisting material or composition employed in the production of the setter. As shown, each column has a longitudinal channel c with one or more cross webs c' .

For supporting the ware, the columns C, D, are provided with shelves on the inner faces which are in opposing relation, the shelves of column C being indicated at E in the drawings, whereas the shelves of column D are shown at E'. The shelves are integral with the columns, and they extend horizontally from said columns, with the shelves E of column C in the same horizontal planes as the shelves E' of column D. The shelves are long enough to support the tiles loaded on the setter, but said shelves are relatively narrow, being of a width to receive the marginal portions of the tiles, as shown in Figure 1. Each shelf E or E' is bounded on one side with a ledge or shoulder e , parallel to the shelf and integral with the column, said ledge functioning as means for directing the tile when sliding it into place on the companion shelves of the two columns.

The tiles are thus supported on the shelves in positions between the columns, and the shelves support the tiles in spaced relation and in a manner to expose the surfaces at the top and bottom to the heat and gases which are free to flow between the components of the setter and between the tiles in a manner to have free and unobstructed access to the coatings applied to the tiles before firing them in the muffle kiln.

In order that there may be no hindrance to the accessibility of heat and gases to the tiles, and particularly the marginal portions thereof, the columns C, D, are provided with vent openings F, the latter occupying such relation to the shelves E, E', as to alternate therewith, whereby heat may flow through openings F in the columns and circulate above the marginal portions of the tiles on the upper glaze coated surfaces of such tiles.

The top member B is in the form of a flat plate extending over the space bounded by the columns C, D, said top member being in one piece with the columns. The plate B and base A join the columns at the ends thereof, and they span the spaces intervening the shelves E, E', the entire middle part of the setter being open and unobstructed and the open space being interrupted to a slight extent only by the formation of the shelves, two series of narrow shelves being provided, one series on each column at the inner side portion thereof.

The setter when out of the kiln is adapted to be loaded with tiles, such as G in Figure 1, said tiles being introduced usually by hand and by sliding the individual tiles into place upon the shelves E, E', each tile resting at

the respective side portions thereof upon two of the shelves. When loaded, the setter and its load are deposited upon a slab H of a conveyor of the kind disclosed in the Prouty patent hereinbefore identified. The loaded setter may be placed upon the conveyor slab crosswise of the latter, as shown at the left in Figure 1; or said loaded setter may be placed with the base thereof lengthwise of the conveyor slab, as shown at the right in Figure 1; but in either position upon the conveyor slab, the loaded setter is anchored relatively to the slab by appropriate separable retaining means operable to hold the setter in a determined relation to the conveyor slab. Various forms of retaining means may be employed, but as shown in Figure 3 it is preferred to provide the conveyor slab H with an upstanding stud or pin h and to provide an opening h' in the base A of the setter, said stud and the opening producing a simple and efficient separable retaining means.

The operation will be readily understood from the foregoing description, but may be summarized briefly as follows:—With the setters out of the kiln, the tiles G are loaded on the setters by sliding each tile horizontally upon companion shelves E, E', of a pair of shelves. The tiles are held by the shelves in spaced order, one above the other, and they occupy the open space of the setter between the columns C, D, and between base A and top B. The loaded setter is deposited upon a slab H of the conveyor, being retained thereon by the draft pin h of the separable retaining means, which pin occupies the opening h' in base A. The loaded setters are carried by the conveyor slabs H into the chambers I of a muffle oven J, Figure 1, said conveyor slabs sliding upon the sole i of the muffle chamber I. With the loaded setters at rest upon the conveyor slabs, the latter are pushed by appropriate means into the muffle chambers wherein they proceed slowly in order to expose the tiles G to the heat flowing within the chambers I. By spacing the tiles within the setters and by the skeleton formation of the setters, the heat circulates freely through all parts of the setter and into the required contact with the coated surfaces of the tiles. When the tiles are thus exposed to the heat within the muffle chambers, the tops B of the setters protect the coated tiles from deposits of foreign matter, such as mortar dropping from the kiln walls and the roof of the muffle chambers, as well as affording protection to the coated tiles from drops of glazing substances which exhibit a tendency to accumulate on the roof of chamber I and to drop, more or less regularly, upon the coated tiles when unprotected by the top member B of the setter. It should be stated that the top member is in overhanging relation to the tier of tiles loaded upon the setter, the area of said top member B exceeding the sizes of tiles

adapted to be loaded on the setter. Further, the tiles are, prior to loading on the setter, prepared by producing a bisque which is fired and then the fired bisque is provided with a coating of appropriate glaze composition, whereupon the coated tiles are loaded on the setters and are moved within the muffle chambers for exposing the coatings to heat in order to fire the glaze. After passing within the muffle chamber the loaded setters are cooled and then the tiles are discharged by removing them from the setter or by dumping the setter for the tiles to slide off the shelves.

Having thus fully described the invention, what I claim as new and desire to secure by Letters Patent is:

1. A ceramic support embodying a plurality of columns, and a plurality of series of shelves on said columns, said shelves extending inwardly from the columns and said shelves of one column being separated and disconnected from the shelves of the other column, each column being provided with perforations for the free flow of heat across said shelves.

2. A ceramic support comprising a base, a plurality of columns, a top member, shelves integral with the columns and extending inwardly therefrom, said columns being connected at their respective ends by the base and the top member and the support intermediate the shelves being open and unobstructed.

3. A ceramic support comprising a base, a top member, a plurality of columns connected by the base and the top member, and shelves integral with the columns and extending inwardly therefrom, said top member overhanging the shelves and affording protection against the lodgment of foreign material upon ceramic products loaded on said shelves.

4. A ceramic support embodying a base, a top member, a plurality of columns connected by said base and top member, and shelves integral with the columns and extending inwardly therefrom, said base being channeled on the undersurface thereof for the free flow of heat below the support.

5. A support for ceramic ware embodying a base, a top member, a plurality of columns, and shelves extending inwardly from said columns, said base being provided with an opening adapted for the reception of a draft pin on a conveyor slot.

6. The combination with a conveyor slab, of a support upward thereon for carrying a load of ceramic products to be fired, and a separable connection between said conveyor slab and the support whereby the support travels with the conveyor slab and displacement of the support relatively to the conveyor slab is arrested.

7. The combination of a conveyor slab provided with a draft lug or pin, and a pre-

fired skeletonized support provided in the bottom thereof with a draft aperture, said support being imposed upon the conveyor slab the stud or pin of which is engaged with said draft aperture to form therewith a separable connection.

8. A support for ceramic ware comprising a base having channels in the underside thereof, a plurality of columns, a top member overhanging the columns and the base, shelves integral with the columns and extending inwardly from the same, said shelves of one column being disconnected from the shelves of the other column, and openings in said columns, said openings of one column alternating with the shelves of the same column.

9. A device of the character described comprising a plurality of columns, and a series of integral shelves on each column, said shelves extending inwardly for a short distance from the columns, one of said columns being slotted to permit the free flow of heat across said shelves.

10. A device of the character described comprising a plurality of columns, shelves formed integrally with each column, said shelves of one column being spaced and disconnected from the shelves of the other column and a ledge formed on each shelf to provide a positioning means for the ceramic articles to be fired.

11. A ceramic support embodying a base, a top member, a plurality of columns connected by said base and top member, and shelves integral with the columns and extending inwardly therefrom, said base having a plurality of channels on the under surface thereof which communicate with the edges of the support and allow a free flow of heat below the support.

12. A support for ceramic ware comprising a one piece molded structure having a base, a top member, a plurality of columns connecting said base and top member, a series of shelves integral with each column, said shelves of one column being spaced and disconnected from the shelves of the other column.

In testimony whereof I have hereto signed
my name this 30th day of June, 1928.

WILLIAM McCOY.
